(57) **CLAIM**

The ornamental design for a drug delivery device with insertion mechanism, as shown and described.

DESCRIPTION

FIG. 1 is a top perspective view of drug delivery device with insertion mechanism in a first position showing our new design;

FIG. 2 is a bottom perspective view thereof;

FIG. 3 is a top plan view thereof;

FIG. 4 is a left side elevational view thereof;

FIG. 5 is a right side elevational view thereof;

FIG. 6 is a front elevational view thereof;

FIG. 7 is a back elevational view thereof;

FIG. 8 is a bottom plan view thereof;

FIG. 9 is a top perspective view thereof;

FIG. 10 is a bottom perspective view thereof;

FIG. 11 is a top plan view thereof;

FIG. 12 is a left side elevational view thereof;

FIG. 13 is a right side elevational view thereof;

FIG. 14 is a front elevational view thereof;

FIG. 15 is a back elevational view thereof; and,

FIG. 16 is a bottom plan view thereof.

The broken line showing of the drug delivery device with insertion mechanism is included for the purpose of illustrating portions of the “article” and forms no part of the claimed design.
